WITCH-FACED PLAYGROUND CLIMBER AND SLIDE

Robert S. Wormser, Hillsdale, Mich., assignor to Game-Time, Inc., Litchfield, Mich., a corporation of Michigan

Filed Mar. 20, 1968, Ser. No. 11,050

Term of patent 14 years

U.S. Cl. D34—5
Int. Cl. D21—03

FIG. 1

FIG. 4

FIG. 3

FIG. 1 is a side elevational view of a witch-faced playground climber and slide in accord with my new design, the opposite side being identical thereto,

FIG. 2 is a front elevational view,

FIG. 3 is a rear elevational view, and

FIG. 4 is a top plan view.

I claim:

The ornamental design for a witch-faced playground climber and slide, substantially as shown and described.
